UNITED STATES PATENT OFFICE.

ASHLEY C. BENNETT, OF MINNEAPOLIS, MINNESOTA.

CARBURETER.

1,260,504.

Specification of Letters Patent. Patented Mar. 26, 1918.

Application filed September 2, 1914. Serial No. 859,787.

To all whom it may concern:

Be it known that I, ASHLEY C. BENNETT, a citizen of the United States, residing at Minneapolis, in the county of Hennepin and 5 State of Minnesota, have invented certain new and useful Improvements in Carbureters, of which the following is a specification.

My invention relates to carbureters and 10 has for its object to provide a carbureter wherein a fixed deflecting member in the path of movement of the primary air and the fuel oil mixing therewith will cause said air and oil to move in an outwardly whirling 15 manner so as to throw particles of uncarbureted oil into contact with the walls of the mixing chamber.

The full objects and advantages of my 20 invention will appear in connection with the detailed description thereof and are particularly pointed out in the claims.

In the drawings, illustrating the application of my invention in one form,—

Figure 1 is a sectional elevation of a carbureter having my improvements applied thereto. Fig. 2 is a section on line 2—2 of Fig. 1. Fig. 3 is a longitudinal section of a part of the device at the end of the feed pipe.

As illustrated, the casing 10 provides the oil chamber in which float 11 regulates the supply of oil in a well known manner so as to keep the level at a point indicated by a dotted line at 12. I provide a casing 13 and 25 chamber 14 which opens into a larger delivery pipe 15 which is connected by another passageway 16 with a source of secondary air, not shown. The lower portion of chamber 14 is closed by plug 17, the top of said 30 plug and the curved inner walls of casing 13 forming a cup-like cavity 18 below the openings 19 for admitting primary air. The plug 17 has a central aperture 20. To 35 the lower portion of this aperture fuel oil is admitted from casing 10 through a duct 21, the extent of opening of the aperture 20 being controlled by a hand-operated needle valve 22. The aperture 20 opens into an 40 expanded portion at the top of the plug 17 45 in which is set a feed pipe 23, and the opening into feed pipe 23 is controlled by a needle valve 24, the shaft 25 of which extends through the center of feed pipe 23 and 50 through a slidable bearing 26 at the upper 55 end of said feed pipe and into the passageway 15, where said valve is controlled by a

lever 27 actuated by the admission of secondary air in a well known way, which forms no part of the invention of this application, and does not need to be described herein. At the top of the feed pipe 23 and surrounding the outside of the bearing portion or sleeve 26 is a spreader member 28 having a series of blades 29 overlapping in a fan-like manner so as to give openings 60 between the blades turned upwardly and obliquely toward the inner walls of the chamber 14. The spreader 28 therefore serves to divide the passageway 14 into a lower portion surrounding the feed pipe 23 65 where the initial mixing of the fuel oil and primary air takes place, and an upper more extended portion above the spreader 28. In this upper passageway the moving column of air and fuel oil is caused to 70 whirl violently so as to impinge upon the inner walls of chamber 14. All particles of fuel oil which pass through the spreader in liquid form are thrown centrifugally 75 against these walls, where said particles 80 are either evaporated from the walls in the current of air or may move back to the spreader member 28 again to be carried up and thrown against the walls.

The advantages of this construction are 85 obvious. The member 28 is stationary and provides a direct baffle for preventing upward movement of large drops of liquid. The whirling movement given the volume 90 of air by the spreader member is such as 95 certainly to cause all drops of liquid to be thrown upon the walls of the passageway. The length of the passageway before the opening if secondary air is reached is such that under normal conditions all of the 100 fuel oil thrown upon the walls of the passageway 14 will be evaporated by the moving current of air. The heavier drops reach the walls first or at the lower portions thereof. Only the very lightest and smallest 105 drops will reach the walls of chamber 14 at the point near the opening therefrom into the passageway 15. The film of oil upon the upper portion of the walls of chamber 14 will therefore be very much 110 thinner than the film toward the bottom thereof. There never will be a volume of drops upon the upper portion of the walls of chamber 14 of sufficient volume so that unevaporated liquid can be carried into the passageway 15, and if the film of oil upon the lower portion of the walls of passageway

way 14 becomes sufficiently heavy so that oil will gravitate downwardly, such oil in passing to the spreader member will again be broken up and thrown back upon the 5 walls of chamber 14. It will readily be apparent, therefore, that my carbureter will produce a highly efficient and satisfactory carbureting of the primary air and will deliver an explosive mixture into the pipe 10 15 for admixture with the secondary air which is free from unevaporated particles or drops of liquid fuel oil.

I claim:

1. A carbureter comprising a casing forming a cylindrical chamber closed at the bottom and provided with air-inlet openings above said bottom for admitting air into the lower portion of the chamber, a fuel feed pipe extending through said bottom a portion 20 of the way into said chamber, said fuel feed pipe being provided with a multiplicity of apertures for permitting fuel oil to be injected directly into the lower portion of said chamber and into the currents of air passing 25 through said inlet openings, and a spreader member fixedly located at the upper end of said fuel feed pipe and having means to cause the mixture of fuel oil and air passing through said spreader member to whirl and 30 throw drops of liquid against the walls of said mixing chamber.

2. A carbureter comprising a casing forming a chamber closed at its bottom having means for admitting primary air thereto 35 above said bottom, an oil feed pipe centrally positioned in said passageway and extending throughout a portion of the length thereof, means above the top of the feed pipe dividing the passageway into two portions 40 through which the mixture of primary air and fuel oil must pass, said dividing means acting upon the current of air and fuel oil to cause the same to whirl and throw drops of liquid upon the walls of the passageway, and means to admit fuel oil to the 45 feed pipe.

3. A carbureter comprising a casing forming a chamber closed at its bottom having means for admitting primary air thereto 50 above said bottom, an oil feed pipe centrally positioned in said passageway and extending throughout a portion of the length thereof, a series of overlapping plates or fins extending in oblique relation from the 55 top of the feed pipe to the walls of said passageway and rigidly secured in position so as to provide a multiplicity of openings

directed toward the walls of said passageway through which the mixture of primary air and fuel oil must pass, whereby said 60 mixture is given a whirling movement and drops of liquid are thrown upon the inner walls of the passageway, and means to admit fuel oil to the feed pipe.

4. A carbureter comprising a casing forming a cylindrical chamber, a plug having a central aperture secured in the bottom of said casing, a hand operative needle-valve extending into the lower end of the central aperture, an air controlled needle valve extending into the upper end of the central aperture, a fluid feed pipe having its lower end positioned in an enlarged portion of the central aperture at the top of said plug, said fuel feed pipe being provided with a multiplicity of apertures for permitting fuel oil to be injected directly into the lower portion of said chamber, means above the bottom of the casing for admitting air into the lower portion of the chamber around said 70 fuel feed pipe, and a spreader member fixedly mounted on the upper end of said fuel feed pipe and having means to cause the mixture of fuel oil and air passing therethrough to whirl and throw drops of the 75 liquid against the walls of the upper portion of said chamber.

5. In combination with the mixing chamber of a carbureter, a stationary spreader member therefor comprising a rim closely fitting said chamber, a central hub and a plurality of overlapping blades extending obliquely from said hub to said rim and a fuel feed pipe upon the upper end of which 80 said central hub is fitted.

6. A carbureter comprising a casing forming a chamber closed at its bottom and having means for admitting primary air thereto above said bottom, an oil feed pipe centrally positioned in said passageway and extending throughout a portion of the length thereof, a spreader member at the top of the feed pipe through which primary air and fuel must pass, and means centrally positioned in said feed pipe and extending through said spreader member for admitting fuel oil into said feed pipe.

In testimony whereof I affix my signature in presence of two witnesses.

ASHLEY C. BENNETT
